RAILWAY BRAKING APPARATUS

Harold C. Clausen, Penn Township, Allegheny County, and Linnie K. Hedding, Wilkinsburg, Pa., assignors to The Union Switch & Signal Company, Swissvale, Pa., a corporation of Pennsylvania

Application November 27, 1943, Serial No. 511,980

4 Claims. (Cl. 303—20)

Our invention relates to railway braking apparatus, and particularly to braking apparatus of the type comprising wheel engaging braking bars located beside a track rail and movable toward and away from the rail into braking and non-braking positions. More particularly, our invention relates to apparatus of the type described in which the braking bars are arranged to be moved to their braking positions by a fluid pressure operated motor and to be restored to their non-braking positions by suitable biasing means such as gravity.

In one form of braking apparatus of the type described, the admission of fluid pressure to, and the exhaust of fluid pressure from, the fluid pressure operated motor is effected through the medium of inlet and exhaust magnet valves, respectively. These valves are energized over a plurality of control circuits, one of which is provided for the inlet valve and another of which is provided for the exhaust valve for each braking pressure desired, and each of which circuits includes a contact operated by a Bourdon tube subjected to the motor pressure. The circuits are so arranged and the Bourdon tubes are so adjusted that for each control pressure for which provision is made the contact included in the circuit for the inlet valve will automatically operate to energize or deenergize the inlet valve according as the motor pressure is below or above a predetermined pressure, while the contact included in the companion circuit for the exhaust valve will automatically operate to energize or deenergize the exhaust valve according as the motor pressure is above or below a predetermined pressure which is slightly higher than the pressure at which the contact for the inlet valve operates, whereby the pressure in the motor cylinder will be automatically held within preselected limits for each braking pressure provided for. With the circuits arranged in this manner when the pressure in the motor cylinder approaches the critical value at which the Bourdon tubes operate the associated contacts, a point is sometimes reached where the contact pressure is very light, and this fact coupled with the inherent resiliency of the Bourdon tubes gives rise to a condition generally referred to as "valve flutter" in which the magnet valve controlled by the contact is caused to become alternately energized and deenergized until a condition of equilibrium is finally reached. This so-called "valve flutter" is undesirable, and one object of our invention is to provide an arrangement of control circuits whereby the flutter can be eliminated

and still affect the desired control with a minimum number of circuit wires.

According to our invention, we connect a condenser across the terminals of the magnet valve, and in order to permit the use of a preferred type of condenser we arrange the control circuit so that the polarity of the current supplied to the inlet magnet is the same for all of the control circuits which are provided for the inlet magnet. 10 We also employ asymmetric units in a manner which enables certain of the circuit wires to be used in more than one of the control circuits.

Other objects and characteristic features of our invention will become apparent as the description proceeds.

Apparatus embodying our present invention is an improvement upon that shown and described in Letters Patent of the United States No. 1,947,638, granted to Herbert L. Bone, on February 20, 1934, for Railway braking apparatus.

We shall describe one form of apparatus embodying our invention, and shall then point out the novel features thereof in claims.

The accompanying drawing is a diagrammatic view showing one form of apparatus embodying our invention.

Referring to the drawing, the reference character 1 designates one track rail of a stretch of railway track, which track rail as here shown, is secured to a rail support 2 mounted on an adjacent pair of the usual crossties 3, only one crosstie being visible in the drawing. Associated with the rail 1 is a car retarder comprising two braking bars A1 and A2 located on opposite sides of rail 1. Each of these braking bars comprises, as usual, a brake beam 4 and a brake shoe 5.

The braking bars A1 and A2 are arranged to be moved toward and away from the rail 1 through the medium of a lever 6 which is pivotally mounted at one end on a pivot pin 8 carried by the rail support 2, and a lever 7 which is pivotally mounted intermediate its ends on the pivot pin 8. The lever 6 is inclined upwardly and extends away from the rail 1 and is provided in its upper surface with a groove 6a which receives the braking bar A1. The one end 7a of the lever 7 is likewise inclined upwardly and extends away from the rail 1 at the opposite side of the rail from the lever 6, and the other end 7b of the lever 7 is inclined downwardly and extends away from the rail 1 below the lever 6. The end 7a of the lever 7 is provided in its upper surface with a groove 7c, similar to the groove 6a in the lever 6, which groove receives the braking bars A2. The parts are so arranged and so proportioned that if the

outer or free ends of the levers 6 and 7 are moved apart, the braking bars will be moved toward the rails into their effective or braking positions. When the braking bars occupy their braking positions, the brake shoes will engage the opposite side faces of a car wheel traversing rail 1, and will retard the speed of the car. The center of gravity of the lever 6 and braking bar A1 is considerably to the left of the pivot pin 8 so that this lever will normally tend to rotate in a counter-clockwise direction about the pivot pin. Similarly, the center of gravity of the lever 7 and braking bar A2 is to the right of the pivot pin 8 so that this lever will normally tend to rotate in a clockwise direction about the pivot pin. It will be apparent, therefore, that when no force is applied to the free ends of the levers 6 and 7 to move them apart, the free ends of these levers will move toward each other, thereby moving the braking bars to their ineffective or non-braking position in which they are illustrated in the drawing.

The levers 6 and 7 are arranged to be moved apart by means of a fluid pressure motor M comprising a cylinder 9 containing a reciprocable piston 10 which is attached to the inner end of a piston rod 11. The cylinder 9 is pivotally connected with the free end of the lever 6 by means of trunnions 12 formed on the side of the cylinder and extending through bifurcations 13 formed on the lever 6, while the piston rod 11 is connected at its free end with the free end 16 of the lever 7 by means of an adjustable eyebolt 14 and pivot pin 15. Fluid pressure may be admitted to the cylinder 9 between the upper end of the cylinder and the piston 10 through an opening 16 which is threaded to receive a pipe 17. When fluid pressure is admitted to the cylinder 9 through the pipe 17 and opening 16, the piston 10 will be forced downwardly and the cylinder 9 upwardly, thereby separating the levers 6 and 7, and hence moving the braking bars toward their effective or braking positions. It will be obvious that when the braking bars are moved to their braking position, they will exert a braking force which is proportional to the pressure of the fluid supplied to the cylinder 9.

The supply of fluid pressure to the cylinder 9 of motor M is controlled by means of two fluid pressure operated poppet valves 22 and 23, which poppet valves, in turn, are controlled by means of two magnet valves V1 and V2. These magnet valves are similar and each comprises a valve stem 18 biased to an upper position by means of a spring 19, and provided with a winding 20 and an armature 21. When valve V1 is energized, as shown in the drawing, valve stem 18 of this valve moves downwardly against the bias exerted by the associated spring 19, and under these conditions a pipe 24 is connected with a pipe 28 which is constantly supplied with fluid pressure, usually compressed air, from a suitable source not shown in the drawing. When valve V1 is deenergized, however, pipe 24 is disconnected from pipe 28 and is connected with atmosphere through a port 52.

When valve V2 is energized, valve stem 18 of this valve moves downwardly, and connects the pipe 28 with a pipe 29; but when valve V2 is deenergized, as shown in the drawing, pipe 28 is disconnected from the pipe 29 and is connected with atmosphere through a port 34.

The two fluid pressure operated poppet valves 22 and 23 are both located in the same valve body 32, and associated with each poppet valve is a

spring 22a or 23a which constantly biases the valve to a closed position. Formed in the valve body 32 above the valve 23, and in axial alignment therewith, is a cylinder 33 containing a reciprocable piston 36 which is operatively connected with the valve 23. The upper end of cylinder 33 is connected with the previously referred to pipe 29, and it will be apparent, therefore, that when valve V2 is deenergized so that pipe 29 is connected with atmosphere, spring 23a will hold valve 23 closed and piston 36 in its upper position, but that, when valve V2 is energized, so that pipe 29 is connected with pipe 28, the fluid pressure which is then supplied to pipe 29 will force piston 36 to its lower position, thus opening valve 23. When valve 23 is opened, cylinder 9 of motor M is connected to pipe 28 through pipe 17, a pipe 41, a chamber 42 formed in valve body 32, valve 22, and a chamber 51 formed in valve body 32; but when this valve is closed, cylinder 9 is disconnected from pipe 28.

The valve body 32 is also formed with a second cylinder 46 containing a reciprocable piston 45 which is operatively connected with the valve 22, and the upper side of which is subjected to the pressure in the pipe 24. When valve V1 is energized, the fluid pressure which is then supplied to pipe 24 forces piston 45 to its lower position thereby opening valve 22, and under these conditions cylinder 9 of motor M becomes connected with atmosphere through pipes 17 and 41, chamber 42, valve 22, a chamber 47 formed in valve body 32, and a pipe 48. When valve V1 is deenergized, however, spring 22a moves valve 22 to its closed position, and piston 45 to its upper position, thus disconnecting cylinder 9 from atmosphere.

It follows from the foregoing that when valve V2 is energized, fluid pressure will be supplied to cylinder 9 from pipe 28, and that when valve V1 is energized cylinder 9 will become connected with atmosphere.

The valves V1 and V2 are controlled in part by a plurality of pressure responsive devices P20-39, P45-55, and P70-80, each comprising a Bourdon tube 25 connected to the pipe 17, and hence subjected to the pressure of the fluid in the region of cylinder 9 between piston 10 and the upper end of the cylinder. Each Bourdon tube 25 controls two contacts 26-26a and 26-26b. The pressure responsive devices P20-39, P45-55 and P70-80 are so constructed and so adjusted that they will operate successively as the pressure in the region of cylinder 9 between the piston 10 and the upper end of the cylinder increases. For example, for all pressures below 20 pounds per square inch, the contact 26-26a of each of these devices is closed. If the pressure exceeds 20 pounds per square inch, however, contact 26-26a of device P20-39 opens; and if the pressure exceeds 30 pounds per square inch, contact 26-26b of device P20-39 closes. In a similar manner, the pressure responsive devices P45-55 and P70-80 are adjusted to open their contacts 26-26a at 45 and 70 pounds per square inch, respectively, and to close their contacts 26-26b at 55 and 80 pounds per square inch, respectively. Of course, these specific pressures are not essential but are only mentioned for purposes of explanation.

The valves V are also controlled by means of a manually operable lever L which, as here shown, is capable of assuming five positions, indicated by dotted lines in the drawing, and designated by the reference characters p1 to p5, inclusive. The lever L controls a plurality of con-

tacts, each designated by the reference character 27, with a distinguishing subscript corresponding to the position of the lever in which the corresponding contact is closed. For example, contact 27-1 is closed in the p1 position of the lever, contact 27-2 in the p2 position of the lever, etc.

Lever L will usually be located at a point remote from the braking apparatus, as is the control cabin of a classification yard car retarder system, and will be connected with the braking apparatus by means of line wires extending from the control cabin to the braking apparatus. As shown in the drawing, lever L occupies its p1, or "off" position, which is the position which it normally occupies when no cars are to be retarded, and all of the contacts of levers L with the exception of contact 27-1, are therefore open. Valve V2 is therefore deenergized, but valve V1 is energized over a circuit which passes from a suitable source of current such as a battery C through line wire 37, the winding of valve V1, wires 49, 35 and 34, an asymmetric unit R1 in its low resistance direction, line wire 38, and contact 27-1 of lever L back to battery C. Since valve V2 is deenergized, pipe 24 is disconnected from pipe 29, and the supply of fluid pressure to cylinder 9 is therefore cut off, and since valve V1 is energized, cylinder 9 is connected with atmosphere. The braking bars are therefore held in their ineffective, or non-braking positions by gravity. The contact 26-26a of each of the pressure responsive devices P is closed, and the contact 26-26b of each of these devices is open.

The apparatus also includes a condenser D, which is connected across the winding 20 of valve V2. This condenser may be of any suitable type, but is preferably an electrolytic condenser because electrolytic condensers are smaller and cheaper than other types for a given capacity. The function of the condenser D will be made clear as the description proceeds.

In explaining the operation of the apparatus as a whole, I shall assume that the operator wishes to make a comparatively light brake application. To do this, he moves lever L from its p1 to its p2 position, thereby opening contact 27-1 of lever L and closing contact 27-2. The opening of contact 27-1 interrupts the circuit which was previously closed for valve V1 at this contact, and valve V1 therefore now becomes deenergized, and disconnects pipe 24 from pipe 28 and connects pipe 24 with atmosphere. When pipe 24 becomes connected with atmosphere, the pressure in this pipe and in the upper end of cylinder 46 decreases rapidly, and as soon as this pressure has decreased to a predetermined value, for example, 15 pounds per square inch, spring 22a closes valve 22, thus disconnecting cylinder 9 from atmosphere. The closing of contact 27-2 completes a circuit for valve V2, and current flows from battery B through contact 27-2 of lever L, line wire 38, contact 26-26a of pressure responsive device P20-30, wire 40, an asymmetric unit R2 in its low resistance direction, wire 50, the winding 20 of valve V2 and condenser D in multiple, and line wire 37 back to battery B. Valve V2 therefore becomes energized and connects pipe 28 with pipe 29 so that fluid at full line pressure is now supplied to the upper end of cylinder 33, thus causing piston 36 to move downwardly, and open valve 23. As was previously pointed out, when valve 23 is opened, pipe 28 becomes connected with pipe 17, and fluid at full line pressure is therefore now supplied to cylinder 9 to

move the braking bars to their effective or braking positions. As soon as the pressure in the upper end of cylinder 9 reaches 20 pounds per square inch, contact 26-26a of pressure responsive device P20-30 will open and will interrupt the circuit just traced for valve V2. Valve V2 will then become deenergized, thus causing valve 23 to become closed, and hence cutting off the supply of fluid pressure to the upper end of the cylinder until the pressure in the motor again decreases below 20 pounds per square inch at which time the resultant reclosing of contact 26-26a of device P20-30 will cause valve V2 to again become energized and again open valve 23 to readmit fluid pressure to the motor. If the fluid in the motor now increases to a pressure of 30 pounds per square inch for any reason, contact 26-26b of pressure responsive device P20-30 will become closed and will complete another circuit for valve V1 passing from battery B through contact 27-2 of lever L, line wire 38, contact 26-26b of pressure responsive device P20-30, wires 34, 35 and 49, the winding 20 of valve V1, and line wire 37 back to battery B. Valve V1 will therefore become energized, and will cause valve 22 to open, thus venting fluid from cylinder 9. Valve 22 will continue to vent fluid from cylinder 9 until the pressure in cylinder 9 has decreased to 30 pounds per square inch, whereupon contact 26-26b will open. When this happens, valve V1 will become deenergized and will cause valve 22 to close, thus preventing further escape of fluid from cylinder 9. It will be seen, therefore, that when lever L occupies its p2 position, the braking bars will be held in their braking positions by a pressure of between 20 and 30 pounds per square inch.

If the operator desires to make a more powerful brake application, he will move lever L to its p3 position in which contact 27-3 is closed. Under these conditions, valve V1 will be deenergized and valve V2 will become energized over a circuit which passes from battery B through contact 27-3 of lever L, line wire 43, contact 26-26a of pressure responsive device P45-55, wire 40, asymmetric unit R2 in its low resistance direction, wire 50, condenser D, and the winding 20 of valve V2 in multiple, and line wire 37 to battery B. Fluid pressure will therefore now be admitted to the upper end of cylinder 9 until the pressure of the fluid in the cylinder increases to 45 pounds per square inch at which time contact 26-26a of pressure responsive device P45-55 will open and will deenergize valve V2. If the pressure in the upper end of cylinder 9 now increases to 55 pounds per square inch, contact 26-26b of pressure responsive device P45-55 will become closed and will complete another circuit for valve V1, this latter circuit passing from battery B through contact 27-3 of lever L, line wire 43, contact 26-26b of pressure responsive device P45-55, wires 35 and 49, winding 20 of valve V1 and line wire 37 back to battery B. The resultant energization of valve V1 will cause valve 22 to open, thus exhausting fluid from the upper end of cylinder 9 in a manner which will be readily understood from the foregoing description. Valve V1 will now remain energized until the pressure has decreased to below 55 pounds per square inch, at which time contact 26-26b of pressure responsive device P45-55 will open and will interrupt the circuit for valve V1. Valve 22 will then reclose and cut off the further exhaust of fluid from cylinder 9. It will be apparent, therefore, that when lever L occupies its p3

position, the braking bars will be held in their braking positions by a pressure of between 45 and 55 pounds per square inch.

If the operator moves lever L to its *p4* position, valve V2 will then become energized over a circuit which passes from battery B through contact 27—4 of lever L, wire 44, contact 26—26a of pressure responsive device P70—80, asymmetric unit R2 in its low resistance direction, wire 50, condenser D in multiple with the winding of valve V2, and line wire 37 back to battery D. Under these conditions fluid will be supplied to the upper end of cylinder 9 until the pressure in the cylinder reaches 70 pounds per square inch, which is the pressure at which contact 26—26a of pressure responsive device P70—80 opens. If the pressure in cylinder 9 now increases to 80 pounds per square inch, contact 26—26b of pressure responsive device P70—80 will become closed and will complete still another circuit for valve V1. This latter circuit for valve V1 may be traced from battery B through contact 27—4 of lever L, line wire 44, contact 26—26b of pressure responsive device P70—80, wire 49, the winding 20 of valve V1 and line wire 37 back to battery B. Valve V1 will therefore become energized and will cause valve 22 to open until the pressure in the upper end of cylinder 9 decreases to 80 pounds per square inch. It will be seen, therefore, that when lever L is moved to its *p4* position, cylinder 9 is supplied with fluid at a pressure of between 70 and 80 pounds per square inch, so that the braking bars exert a corresponding braking force.

It should be particularly pointed out that whenever valve V2 becomes energized with lever L in any one of the positions previously described, the condenser D becomes charged, and, as a result when this valve subsequently becomes deenergized due to the opening of the contact 26—26a of any one of the pressure responsive devices P20—30, P45—55 or P70—80, the condenser discharges through the winding 20 of valve V2. Furthermore, the condenser provides a shunt path for any current which may be induced in the winding 20 due to the decaying flux in the magnetic current of the magnet valve, whereby the valve V2 is caused to remain closed for an interval of time after the contact 26—26a opens. The length of this time interval depends upon the proportioning of the parts, and the parts are preferably so proportioned that sufficient fluid will be admitted to cylinder 33 at any time after the contact 26—26a which is then effective to control the energization of valve V2 opens, to cause valve 23 to open and admit enough fluid to the cylinder 9 to prevent this contact from remaining in an unstable state where it will cause the valve to flutter, but that, this fluid will not be sufficient in volume to cause the associated contact 26—26b to become closed and energize valve V1 to vent fluid to atmosphere.

It should also be particularly pointed out that when lever L occupies its *p2*, *p3* or *p4* position valve V2 is always supplied with current of the same polarity, so that it is possible for the condenser D to be of the electrolytic type. This is an advantage due to the smaller size and less cost of this type of condenser for a given capacity.

If the operator desires to cause the braking bars to exert their maximum braking force, he moves lever L to its *p5* position. Under these conditions valve V2 becomes energized and subsequently remains energized over a circuit which passes from battery B through contact 27—5 of lever L, line wire 30, wire 50, condenser D in multiple with the winding 20 of valve V2, and line

wire 37 back to battery B. The energization of valve V2, of course, causes valve 23 to open, and when valve 23 becomes opened, fluid at full line pressure is supplied to the upper end of cylinder 9. It will be apparent therefore that under these conditions the braking bars will be held in their braking positions by fluid at full line pressure.

It should be observed that if the operator moves lever L from a position corresponding to a higher braking force to a position corresponding to a lower braking force, the apparatus immediately and automatically reduces the braking pressure to a value corresponding to the new position of the lever in a manner which will be apparent from the drawing without tracing the sequence of operation in detail.

When lever L occupies any one of its *p2*, *p3*, *p4* or *p5* positions, so that the braking bars occupy their braking positions and the operator wishes to restore the braking bars to their non-braking position in which they are illustrated in the drawing, he will restore lever L to its *p1* or "off" position. When he does this, all circuits previously traced for valve V2 will be interrupted, and the circuit previously described for valve V1 including contact 27—1 of lever L will become closed. Valve V2 will therefore become deenergized and valve V1 will become energized thus causing valve 23 to close and valve 22 to open. As a result, the supply of fluid pressure to the upper end of cylinder 9 will be cut off, and the fluid which was previously supplied to this end of the cylinder will be vented to atmosphere. The braking bars will therefore move under the influence of gravity to their ineffective or non-braking positions. When the braking bars reach their non-braking positions, all parts are restored to the position in which they are shown in the drawing.

It should be particularly pointed out that the use of the asymmetric units R1 and R2 in the circuits for the valves V1 and V2 in the manner described enables the number of line wires required between the lever and the retarder to be reduced to a minimum and at the same time makes it possible to arrange the circuits so that valve V2 will always be supplied with current of the same polarity.

Although we have herein shown and described only one form of railway braking apparatus embodying our invention, it is understood that various changes and modifications may be made therein within the scope of the appended claims without departing from the spirit and scope of our invention.

Having thus described our invention, what we claim is:

1. In combination, a fluid pressure motor, a pressure responsive device subjected to the pressure of the fluid in said motor and provided with a first contact which becomes opened or closed according as the pressure of the fluid in said motor is above or below a first predetermined pressure and with a second contact which becomes closed or opened according as the pressure of the fluid in said motor is above or below a second predetermined pressure somewhat higher than said first pressure, a first magnet valve effective when energized to cause fluid to be admitted to said motor, a second magnet valve effective when energized to cause fluid to be exhausted from said motor, a pair of manually operable contacts, a pair of line wires, two sources of electromotive force one effective to supply said line wires with current of one polarity and the other effective

to supply said line wires with current of the other polarity according as the one or the other of said manually operable contacts is closed, means including said first contact and a first asymmetric unit poled to pass current of said one polarity only for connecting said first magnet valve with said wires, means including said second contact for at times connecting said second magnet valve with said wires, and means including an asymmetric unit poled to pass current of said other polarity only for at other times connecting said second magnet valve with said wires.

2. In combination, a fluid pressure motor, a pair of line wires which are reversibly supplied with current, a pressure responsive device subjected to the pressure of the fluid in said motor and provided with a first contact which becomes opened or closed according as the pressure of the fluid in said motor is above or below a first predetermined pressure and with a second contact which becomes closed or opened according as the pressure of the fluid in said motor is above or below a second predetermined pressure somewhat higher than said first pressure, a first magnet valve effective when energized to cause fluid to be admitted to said motor, a second magnet valve effective when energized to cause fluid to be exhausted from said motor, means including said first contact and an asymmetric unit poled to pass current of one polarity but not the other for connecting said first magnet valve with said wires, means including said second contact for at times connecting said second magnet valve with said wires, means including an asymmetric unit poled to pass current of said other polarity for at other times connecting said second magnet valve with said wires, and a condenser connected in multiple with said first magnet valve.

3. Railway braking apparatus comprising a braking bar located in the trackway beside a track rail, a fluid pressure motor for moving said braking bar toward the track rail into a braking position in which it will engage a part of a car to retard the speed of the car, a first magnet valve effective when energized for connecting said motor with a source of fluid pressure, a second magnet valve effective when energized for connecting said motor with atmosphere, a lever having an "off" and a plurality of "on" positions, two sources of fluid pressures, a plurality of devices responsive to the pressure of the fluid in said motor, each said device being provided with a first contact which is opened or closed according as the motor pressure is above or below a first predetermined pressure and a second contact which is closed or opened according as the motor pressure is above or below a second predetermined pressure which is higher than said first pressure, said devices each being responsive to predetermined pressures which are different from the pressures at which the other devices respond; a first energizing circuit for said second magnet valve including a first one of said sources, a first contact of said lever closed only in the "off" position and an asymmetric unit connected to pass current of the polarity of said first source; a plurality of other energizing circuits for said second magnet valve each including the other source of current, a contact of said lever closed in a different one of

the "on" positions of the lever and the second contact of a different one of said pressure responsive devices; a plurality of energizing circuits for said first magnet valve, each including said other source, a contact of said lever closed in a different one of the "on" positions of said lever, the first contact of a different one of said pressure responsive devices, and an asymmetric unit poled to pass current of the polarity supplied to said circuits by said other source, said first energizing circuit including certain of the wires included in the other circuits for both magnets and said two sources being poled in the opposite directions in the respective circuits in which they are included.

4. Railway braking apparatus comprising a braking bar located in the trackway beside a track rail, a fluid pressure motor for moving said braking bar toward the track rail into a braking position in which it will engage a part of a car to retard the speed of the car, a first magnet valve effective when energized for connecting said motor with a source of fluid pressure, a second magnet valve effective when energized for connecting said motor with atmosphere, a lever having an "off" and a plurality of "on" positions, two sources of fluid pressure, a plurality of devices responsive to the pressure of the fluid in said motor, each said device being provided with a first contact which is opened or closed according as the motor pressure is above or below a first predetermined pressure and a second contact which is closed or opened according as the motor pressure is above or below a second predetermined pressure which is higher than said first pressure, said devices each being responsive to predetermined pressures which are different from the pressures at which the other devices respond; a first energizing circuit for said second magnet valve including a first one of said sources, a first contact of said lever closed only in the "off" position and an asymmetric unit connected to pass current of the polarity of said first source; a plurality of other energizing circuits for said second magnet valve each including the other source of current, a contact of said lever closed in a different one of the "on" positions of the lever and the second contact of a different one of said pressure responsive devices; a plurality of energizing circuits for said first magnet valve, each including said other source, a contact of said lever closed in a different one of the "on" positions of said lever, the first contact of a different one of said pressure responsive devices, and an asymmetric unit poled to pass current of the polarity supplied to said circuits by said other source; said first energizing circuit including certain of the wires included in the other circuits for both magnets and said two sources being poled in the opposite directions in the respective circuits in which they are included, all of the circuits for said first magnet valve being arranged to supply said first valve with current of the same polarity, and an electrolytic condenser connected across said first valve in the direction to become charged when said first valve becomes energized, whereby valve flutter is eliminated when said first valve becomes deenergized due to the operation of any one of the first contacts of said pressure responsive devices.
